MEANS FOR THE CONTROLLED INJECTION OF
A LIQUID ADDITIVEJohn D. Bennett, Richardson, Tex., assignor to Sun Oil
Company, Philadelphia, Pa., a corporation of New
JerseyFiled June 10, 1960. Ser. No. 35,172
15 Claims. (Cl. 137—564.5)

This invention relates to means for injecting a controlled amount of liquid additive into a fluid line, and more particularly to such means operated by the pressure of such fluid.

It is frequently desired to add certain chemical agents to fluids for the purpose of inhibiting corrosion, for example, and this may be effected by injecting the additive into a fluid line. Generally, it is desirable to effect automatic continuous and uniform injection of the additive in order to achieve the maximum beneficial effects.

Prior art methods of injection have generally employed pumps powered by auxiliary means or devices operable manually at intervals. Obviously the attainment of a continuous and uniform injection rate automatically, without the necessity for auxiliary operating means that are susceptible to failure, affords decided advantages.

Accordingly, it is an object of the invention to provide means for automatically injecting an additive continuously and uniformly into a fluid line or other container.

It is a further object to effect the operation of such means by utilizing pressure in the line.

It is a further object to provide simple means for regulating the rate of injection of the additive.

Further objects and advantages will become apparent from the following description taken in conjunction with the accompanying drawings, in which:

FIGURE 1 is an axial cross-section of the pump;
FIGURE 2 is a plan view of the pump;

FIGURE 3 is a vertical section of a valve block, taken on line 3—3 of FIGURE 1, with the connecting tube and packing assembly removed; and

FIGURE 4 is a cross-section of a cylinder head taken on line 4—4 of FIGURE 2.

While the invention is more broadly applicable, it is of major commercial value in introducing corrosion inhibitors into pipe lines containing petroleum products, and for simplicity will be so described.

Referring to FIGURE 1, the apparatus, which for purposes of description will be referred to hereafter as a "pump," is intended to inject automatically a small quantity of additive into a line 2 in which liquid, or possibly a gas, is flowing. The housing of the pump comprises a pair of cylinders 3 and 5, preferably of stainless steel, which are fitted in annular grooves 6 and 8, respectively, in a central valve block 10. The left end of cylinder 3 is closed by a head 14 having an annular groove 16 into which the cylinder 3 is fitted. Likewise, the right end of cylinder 5 is closed by a head 18 having an annular groove 20 into which the cylinder 5 is fitted. Annular grooves 6, 8, 16 and 20 contain sealing gaskets formed, for example, of neoprene rubber. This assembly is held together by tie rods 21 passing through the valve block 10 and bolted at the heads 14 and 18.

A tube 22 is reciprocable through a central opening and packing assembly, indicated at 24, in the valve block 10. The packing assembly comprises a resilient ring 26, of neoprene rubber for example, compressed between a pair of metal rings 28 and 30, these parts being held in place by a snap ring 32. A piston 34, having a resilient piston ring 36, is mounted on a plug 38 permanently fitted within the left end of tube 22. Piston 34 is held against the plug 38 and a sealing ring (or "O-ring") 40 therein

2

by a cotter pinned nut 42 and washer 44 on the shank of plug 38. A second piston 46, having a piston ring 48, is mounted on a plug 50 permanently fitted within the right end of tube 22. Piston 46 is held against plug 50 and a sealing ring 52 therein by a cotter pinned nut 54 and washer 56 on the shank of plug 50. Piston rings 36 and 48 preferably are formed of a material such as neoprene rubber. It will be noted that a plurality of openings 58 are provided in the tube 22 adjacent the left end thereof, the effect of these openings 58 being mentioned hereafter. From the description thus far it will be evident that four separate chambers, of variable volume, are defined within the cylinders 3 and 5, and these chambers will be referred to hereafter as A, B, C and D.

A sight glass needle valve provided in block 10 is generally indicated at 60 and will be briefly described, although it will be understood that such valves are conventional and commercially available. Referring to FIGURE 3, a drilled passage 62 extends downwardly into block 10, terminating at and connecting with a further passage 64 drilled from the left side of block 10 and communicating with chamber B. A transparent glass or plastic tube 66 is seated in passage 62, being sealed by resilient rings 68, and is visible through a drilled through passage 67 in block 10. Closely fitted within an enlarged bore 70, and sealed by a sealing ring 74, is a bushing 72 which is seated against the upper end of tube 66 and fixed in place by a snap ring 76. The stem 78 of the needle valve has a tapered portion 77 adapted to mate with a corresponding tapered seat 79, in the bushing 72. A pointed extension 80 of stem 78 passes, with clearance, through the bushing 72 to effect the formation of drops of liquid flowing through the valve, which drops may be visually observed through the transparent tube 66. Stem 78 is threaded into bushing 72 and has a knob 82 by which the stem 78 may be rotated to adjust the clearance between the tapered portion 77 and seat 79. A fluid conduit 86 is tapped into block 10 and communicates with a space 84 defined between the bushing 72 and bore 70. Through a port 87 in bushing 72 liquid may flow from space 84 around the valve stem 78, forming drops which fall downwardly through passage 62 and past the window-like tube 66. It will be understood that by the adjustment of knob 82 the rate of flow of liquid from conduit 86 through needle valve 60 and into chamber B may be regulated.

Referring particularly to FIGURE 4, the other end of conduit 86 is tapped into head 14 and communicates with chamber A through an internal passage 88. A ball check valve 90 permits the flow of liquid through conduit 86 only in the direction from chamber A to needle valve 60.

A packed felt vent, of conventional nature, is provided in passages 92 and 93, providing communication between chamber B and the exterior of the pump.

Referring to FIGURE 3, a transverse passage 94 is drilled into block 10 from the side thereof and communicates with chamber B, and connects with a vertical passage 96 into which is tapped a fluid conduit 98. Conduit 98 is tapped at its other end into head 14 and communicates with chamber A through internal passages 100 and 102. A ball check valve 104 is provided to permit the flow of liquid in conduit 98 only in the direction from chamber B to chamber A.

A further valve, generally indicated at 106, is provided in a downwardly extending and externally threaded neck 108 of valve block 10. Neck 108 has three inwardly extending bores 110, 112, and 114 of progressively decreasing diameters, and a cylindrical member 113 positioned therein has its upper end 114 closely fitted and seated within the upper and smaller bore 114, a liquid tight seal being

provided by an "O-ring." A space 116 is defined between member 113 and bore 112, and also between member 113 and a ring 118 seated and sealed within the upper end of bore 110. Member 113 is fitted within and sealed against the lower portion of ring 118 at 120, and the outer diameters of member 113 and ring 118, with the exception in the latter case of shoulder 122, are less than the diameter of bore 110 to provide a space 124. The reduced lower end 128 of member 113 is received and sealed within a flanged nipple 126, and a snap ring 130 retains the complete valve assembly within block 10. A passage 132 provides communication between space 124 and the interior of a fluid pipe line when, as shown in FIGURE 1, the pump is installed by screwing the externally threaded neck 108 into a fitting 133 in the line 2.

A fluid conduit 134 is tapped at one end into block 10 and at its other end it is tapped into head 18 for communication with chamber D through a drilled passage 136. At the valve block 10, fluid conduit 134 communicates with space 124. Central bores 138 and 139, of relatively smaller and larger diameters respectively, extend through the center of member 113, and a short piston 140 is urged upwardly in bore 139 by a coil spring 142 bottomed against nipple 126. Nipple 126 is so named because it has a long tubular neck 144 so that it will project well into the stream of fluid in pipe line 2, and has a central passage 146 communicating with the interior of member 113. A port 148 provides communication between space 116 and the space within lower bore 139 when piston 140 is in its extreme upper position, which is the position shown in FIGURE 3. As shown particularly in FIGURE 1, a tube 150 extends from the upper portion of chamber C, curving around tube 22, and is permanently fitted into block 10 for communication with the space 116. Thus it will be seen that when piston 140 is in its extreme upper position, which is the position shown in FIGURE 3, communication will be established between chamber C and the fluid line 2 through a path traceable as follows: tube 150, space 116, port 148, bore 139 and bore 146. On the other hand, when piston 40 is forced downwardly—by liquid pressure acting from above—communication will be established between chamber C and the space within upper bore 138 through a path traceable as follows: tube 150, space 116, port 148 and bore 138. As to chamber D, communication always is present between this chamber and the fluid line 2 through a path traceable as follows: passage 136, conduit 134, space 124, and passage 132.

A passage 152 is drilled transversely into block 10, terminating at and connecting with the bore 138. A fluid line 154 is tapped into passage 152, and there are schematically illustrated a hand pump 156 and a reservoir tank 158 for the liquid additive to be pumped into the fluid line 2. Thus, when pump 156 is operated to pump liquid additive through passage 152 and bore 138 the pressure of the liquid will force piston 140 downwardly to a position below port 148, thereby effecting the flow of liquid additive through port 148, space 116 and tube 150 into chamber C. This matter of operation will be better understood from the following description of the overall pump operation.

Chambers A and B are filled with what will be referred to hereafter as a "control oil," and which preferably is an all weather medium viscosity lubricating oil. At the time of assembly of the pump, and prior to putting it into operation, chambers A and B, as well as the interior of tube 22, are filled with control oil. This filling is effected with the pistons 34 and 46 and tube 22 at their extreme left hand position as viewed in FIGURE 1. With chambers A and B thus filled, air will be expelled therefrom and will exist only in the fluid conduit 86 and sight needle valve 60.

The pump is installed by screwing the neck 108 into the pipe fitting 133. Fluid, which will be referred to hereafter as "line fluid," from line 2 will flow upwardly through port 132, space 124 and conduit 134 into cham-

ber D. The pressure of line fluid thereby existing in chamber D acts upon piston 46 in a direction toward the left (FIGURE 1), tending to expel air, or liquid additive left over from previous use, from chamber C through tube 150, space 116, port 148 and nipple 126 into line 2. (It will be noted that since tube 150 opens into chamber C at the upper space thereof, air will be expelled from chamber C in preference to left over liquid additive.) With piston 46 at its extreme left hand position, the filling of chamber C with liquid additive is begun by the manual or motorized operation of a pump such as schematically illustrated herein at 156. Liquid additive is stored in reservoir 158, and by the operation of pump 156 it is pumped through conduit 154 into passage 152 and bore 138. The total force of the pumped liquid additive acting on the upper side of piston 140 is greater than the combined force of the spring 142 and the fluid pressure acting upwardly on the underside of piston 140, the latter pressure being that of the fluid in line 2. Therefore, piston 140 is forced downwardly to a position below port 148, thereby permitting additive to flow through port 148, space 116 and tube 150 into chamber C. The total force of the pumped liquid additive pressure in chamber C acting to the right against piston 46 is greater than the total force of the line fluid pressure in chamber D acting to the left against piston 46, and therefore piston 46 is driven to the right (FIGURE 1), displacing line fluid from chamber D into line 2 via conduit 134, space 124 and passage 132. It will be understood that since the control oil pressure within tube 22 is substantially atmospheric, control oil pressure acting to the right on plug 50 has little or no effect on the above operation. In the course of movement of piston 46 to the right, corresponding movement of piston 34 displaces control oil from chamber B to chamber A via conduit 98 and check valve 104.

The operation of pump 156 is continued until chamber C has been pumped full of liquid additive, i.e. when piston 46 has been moved to its extreme right hand position as viewed in FIGURE 1. As the operation of pump 156 is discontinued, the combined force of spring 142 and the line fluid pressure acting on the underside of piston 140 again is sufficient to move the same upwardly to the position shown in FIGURE 3, thereby re-establishing communication between chamber C and line 2 via tube 150, space 116, port 148, bore 139 and nipple 126. At this point the additive in chamber C and the line fluid in chamber D both are at the line fluid pressure. However, control oil at atmospheric pressure rather than additive at line pressure exists within tube 22, and therefore the pressure acting to the right against plug 50 is negligible. The effective working area, then, at the left of piston 46, excluding the cross-sectional area of tube 22, is less than the effective working area at the right of piston 46, and a differential area is provided which causes line fluid pressure in chamber D to move piston 46 to the left. Additive thereby is forced out of chamber C through tube 150 and is discharged through nipple 126 into the line 2.

As piston 46 moves to the left, it drives piston 34 to the left also, forcing control oil out of chamber A through check valve 90 and needle valve 60. However, the rate of movement of piston 34 to the left, and therefore the rate of emptying of chamber C, is limited by the rate at which control oil can be displaced from chamber A and flow past needle valve 60. Thus, by the setting of knob 82 the resistance to flow past the valve stem extension 80 may be adjusted. The small amount of control oil that is permitted to flow readily forms into drops at the pointed end of extension 80, and through the window-like tube 66 each drop may be observed as it forms. The rate of flow of control oil from chamber A through conduit 86 and needle valve 60 is directly proportional to the rate at which liquid additive is displaced from chamber B and injected into line 2, and therefore the frequency of the drops of control oil observed serves as a direct indication of the additive injection rate.

Certain aspects of volume changes involved in operation of the pump will now be explained. Chambers A and B were filled with control oil when piston 34 was in the position at its left hand limit of movement as viewed in FIGURE 1. Therefore, the volume of control oil initially provided approximately corresponds to the volume of cylinder 3, plus a small volume of control oil represented by the space within the portion of tube 22 then extending to the right of the left side of the block 16. However, assume next that piston 34 is in the position at its extreme right hand limit of movement. Now, the total volume available to contain control oil corresponds approximately to the volume of cylinder 3 and, in addition, the total volume within tube 22 along its entire length. Therefore, although when the piston 34 is at the left there is no room for air in chambers A and B, when piston 34 is at the right a substantial air space is provided. During the filling of chamber C with additive, when pistons 34 and 46 move to the right, the total volume available for control oil increases and air is drawn through the felt vents 92, 93 into chamber B. Then, when the filling of chamber C is completed and pistons 34 and 46 again move to the left, a substantial air space will exist in chamber B into which the drops of control oil emanating from needle valve 60 may fall. It will be evident that if an air space does not exist within the vertical passage 62, this passage will be filled with oil and the formation of drops of control oil that are visible could not take place. As movement of pistons 34 and 46 to the left continues, the volume of air in the upper portion of chamber B will progressively decrease, with air being expelled to the atmosphere through felt vents 92, 93. By the time chamber C is completely emptied of liquid additive and piston 34 reaches its extreme left hand position, chambers A and B both will be filled to the top with control oil. When chambers A and B are filled with control oil, as previously described, if the vertical passage 62 and conduit 86 also are filled with control oil, then when the piston 34 reaches its extreme left hand position oil will begin to rise in passage 62 until it prevents the formation of drops of oil at the extension 80. This discontinuation of the free formation of drops of oil may serve as a sign that the chamber C is empty or almost empty and must be refilled with additive. This expedient is not necessary, however, because, in practice, for a given adjustment of the needle valve 60 the time which elapses during the emptying of the pump will be known through experience. In regard to the emptying period of the pump it should be borne in mind that in general an inhibitor pump is intended to inject a very small quantity of additive in proportion to the line fluid flow rate, and the rate of injection might be in terms of a certain number of drops of additive per minute. Thus the pump may take days or weeks to empty.

It will be understood that various departures from the specifically disclosed embodiments may be made without departing from the scope of the invention as defined by the following claims.

What is claimed is:

1. In combination with a pump having a movable pumping member and adapted for injecting an additive into a conduit or the like containing a fluid under pressure, a closed cylinder, a piston reciprocable in said cylinder dividing the same into separate chambers, means transmitting movement of said pumping member to said piston for movement thereof relative to said cylinder, a liquid within said cylinder, a bypass line for the flow of said liquid between the chambers in said cylinder, and means indicating the occurrence and rate of flow in said bypass line, thereby to serve as an indication of pump operation.

2. Means for injecting an additive into a conduit or the like containing a fluid under pressure, comprising a closed cylindrical structure having a wall member dividing the same into first and second cylinders, a first piston in one of said cylinders and a second piston in the other of said cylinders, said pistons defining in each cylinder a pair of

chambers, a rod connecting said pistons and extending through a fluid sealed opening in said wall member, a bypass line for the flow of liquid between the first and second chambers of said first cylinder, means for regulating the rate of flow through said line, means for indicating said rate of flow, means providing independent communication between said conduit and the respective chambers of said second cylinder, the working area of said second piston being less at the side thereof in said first chamber than at the side in the second chamber of said second cylinder, and means for intermittently filling the last-mentioned first chamber with additive.

3. Means for injecting an additive into a conduit or the like containing a fluid under pressure, comprising first and second closed cylinders, first and second pistons reciprocable respectively in said cylinders and defining in each a pair of chambers, means providing independent communication between said conduit and the respective chambers of said first cylinder, the working area at one side of said first piston being less than at the other side, means for intermittently filling the chamber of said first cylinder at said first side with additive, means transmitting movement of said first piston to said second piston for movement of the latter relative to the second cylinder, a liquid within said second cylinder, a bypass line for the flow of said liquid between the chambers in said second cylinder, and means for indicating the rate of flow in said bypass line.

4. Means for injecting an additive into a conduit or the like containing a fluid under pressure, comprising first and second closed cylinders, first and second pistons reciprocable respectively in said cylinders and defining in each a pair of chambers, means providing independent communication between said conduit and the respective chambers of said first cylinder, the working area at one side of said first piston being less than at the other side, means for intermittently filling the chamber of said first cylinder at said first side with additive, means transmitting movement of said first piston to said second piston for movement of the latter relative to the second cylinder, a liquid within said second cylinder, a bypass line for the flow of said liquid between the chambers in said second cylinder, and means for regulating the rate of flow in said line, whereby the movement of said first piston is controlled.

5. Means for injecting an additive into a conduit or the like containing a fluid under pressure, comprising first and second closed cylinders, first and second pistons reciprocable respectively in said cylinders and defining with each a pair of chambers, means providing independent communication between said conduit and the respective chambers of said first cylinder, the working area at one side of said first piston being less than at the other side, means for intermittently filling the chamber of said first cylinder at said first side with additive, means transmitting movement of said first piston to said second piston for movement of the latter relative to the second cylinder, a liquid within said second cylinder, a bypass line for the flow of said liquid between the chambers in said second cylinder, and a valve regulating the flow of liquid in said line.

6. Means for injecting an additive into a conduit or the like containing a fluid under pressure, comprising first and second closed cylinders, first and second pistons reciprocable respectively in said cylinders and defining with each a pair of chambers, means providing independent communication between said conduit and the respective chambers of said first cylinder, the working area at one side of said first piston being less than at the other side, means for intermittently filling the chamber of said first cylinder at said first side with additive, means transmitting movement of said first piston to said second piston for movement of the latter relative to the second cylinder, a liquid within said second cylinder, a bypass line for the flow of said liquid between the chambers in said second cylinder, and a restriction in said line regulating the flow of liquid therein.

7. Means for injecting an additive into a conduit or the like containing a fluid under pressure, comprising first and second closed cylinders, first and second pistons reciprocable respectively in said cylinders and defining in each a pair of chambers, means providing independent communication between said conduit and the respective chambers of said first cylinder, the working area at one side of said first piston being less than at the other side, means for intermittently filling the chamber of said first cylinder at said first side with additive, means transmitting movement of said first piston to said second piston for movement of the latter relative to the second cylinder, a liquid within said second cylinder, a bypass line for the flow of said liquid between the chambers in said second cylinder and around said second piston, means for regulating the rate of flow in said line, a second bypass line for the flow of liquid between the chambers of said second cylinder, and a check valve in said second line permitting liquid flow therein only during operation of said filling means.

8. Means for injecting an additive into a conduit or the like containing a fluid under pressure, comprising a closed cylindrical structure having a wall member dividing the same into first and second cylinders, a first piston in one of said cylinders and a second piston in the other of said cylinders, said pistons defining in each cylinder a pair of chambers, a hollow connecting rod connecting said pistons and extending through a fluid sealed opening in said wall member, the interior of said rod being sealed against communication with the interior of a first chamber of said second cylinder but having means providing such communication with a first chamber of the first cylinder, a bypass line for the flow of liquid between the first and second chambers of said first cylinder, means for regulating the rate of flow through said line, means for indicating said rate of flow, means providing independent communication between said conduit and the respective chambers of said second cylinder, the working area of said second piston being less at the side thereof in said first chamber than at the side in the second chamber of said second cylinder, and means for intermittently filling the last-mentioned first chamber with additive.

9. Means according to claim 8, including a second bypass line for the flow of liquid between the chambers of the first cylinder, and a check valve in said second line permitting said flow therein only from the first to the second of the last-mentioned chambers.

10. Means according to claim 8, including a check valve in said bypass line permitting said flow therein only from the said second to the first of the chambers in said first cylinder.

11. Means according to claim 8, including a check valve in said bypass line permitting said flow therein only from the said second to the first of the chambers in said first cylinder, a second bypass line between the last-mentioned chambers, and a check valve in said second line permitting

flow therein only from the first to the second of the last-mentioned chambers.

12. Means according to claim 8, wherein said regulating and indicating means comprise a needle valve having a windowlike opening for the visual observation of liquid flowing through said needle valve.

13. Means for injecting an additive into a conduit or the like containing a fluid under pressure, comprising a closed cylinder, a piston reciprocable within said cylinder and defining therewith a pair of chambers, the working area at one side of said piston being less than that of the other side, means providing communication between the conduit and the chamber at said other side of the piston, means defining a passage for the injection of additive from the other chamber into the conduit, a pump for intermittently filling said other chamber, and means responsive to operation of said pump to close said passage to flow therethrough.

14. Means for injecting an additive into a conduit or the like containing a fluid under pressure, comprising a closed cylinder, a piston reciprocable within said cylinder and defining therewith a pair of chambers, the working area at one side of said piston being less than that of the other side, means providing communication between the conduit and the chamber at said other side of the piston, a pump, a two-way valve structure having a first position providing communication between the other chamber and the conduit and a second position interrupting said communication and establishing communication between said other chamber and said pump, said pump being adapted to fill said other chamber with additive when the valve is in said second position, the valve being moved to said second position by the operation of said pump.

15. Means for injecting an additive into a conduit or the like containing a fluid under pressure, comprising a closed cylinder, a piston reciprocable within said cylinder and defining therewith a pair of chambers, the working area at one side of said piston being less than that of the other side, means providing communication between the conduit and the chamber at said other side of the piston, a pump, a two-way valve structure having a first position providing communication between the other chamber and the conduit and a second position interrupting said communication and establishing communication between said other chamber and said pump, said pump being adapted to fill said other chamber with additive when the valve is in said second position, the valve being responsive to the pressure of additive pumped by said pump to move to said second position.
